UNITED STATES PATENT OFFICE

172,129

ELECTRIC BLENDER

Joseph R. Corbett, Cincinnati, Ohio

Application December 31, 1953, Serial No. 28,296

Term of patent 14 years

(Cl. D89--1)

To all whom it may concern:

Be it known that I, Joseph R. Corbett, a citizen of the United States, residing at Cincinnati, in the county of Hamilton and State of Ohio, have invented a new, original, and ornamental Design for an Electric Blender, of which the following is a specification, reference being had to the accompanying drawing, forming a part thereof.

Figure 1 is a perspective view of an electric blender showing my new design.

Figure 2 is a side elevational view thereof.

Figure 3 is a side elevational view of the blender

showing the side thereof which is to the right in Figure 2.

I claim:

The ornamental design for an electric blender, substantially as shown.
